Des. 212,529

Patented Oct. 29, 1968

212,529

ORNAMENTAL RAILING

Louis Blum and William J. Horgan, Jr., Pittsburgh, Pa.,
assignors to Blumerraft of Pittsburgh, Pittsburgh, Pa., a
firm

Filed Dec. 19, 1967, Ser. No. 9,851

Term of patent 14 years

(Cl. D13—7)

Fig. 4

Fig. 5

Fig. 6

FIG. 1 is a perspective view looking from one side at a railing embodying our new design;

FIG. 2 is a side elevation of the railing of FIG. 1;

FIG. 3 is an enlarged view of the subject matter illustrated within the bracket III—III of FIG. 2;

FIG. 4 is a partial top view of a railing embodying our new design;

FIG. 5 is an end view of a railing embodying our new design; and

FIG. 6 is an end view of a modified form of the railing wherein the lower rail structure is broad and the post are connected to the bottom side of said rail structure.

The dominant features of the design are shown in solid lines.

The railing repeats as indicated and is shown fragmentarily to indicate indeterminate length.

We claim:

The ornamental design for an ornamental railing, as shown and described.
